G. C. RUHMANN ET AL.

FUEL ECONOMIZER AND CARBON REDUCER

Filed Jan. 30, 1924

UNITED STATES PATENT OFFICE.

GROVER C. RUHMANN AND ELO E. PARKER, OF KENEDY, TEXAS.

FUEL ECONOMIZER AND CARBON REDUCER.

Application filed January 30, 1924. Serial No. 689,447.

To all whom it may concern:

Be it known that we, GROVER C. RUHMANN and ELO E. PARKER, citizens of the United States, residing at Kenedy, in the county of Karnes and State of Texas, have invented new and useful Improvements in Fuel Economizers and Carbon Reducers, of which the following is a specification.

This invention relates to a fuel economizer and carbon reducer for use in connection with automobile and other internal combustion motors, the main object of the invention being to provide a device for drawing off the steam and vapor generated in the radiator of an automobile or other water-cooled internal combustion motor, separating the steam and vapor from the moisture, and supplying the steam and vapor to the carbureter for admixture to the fuel charge so as to secure more complete combustion of the fuel and greater working power therefrom, and so as to reduce the deposits of carbon to a material extent.

A further object of the invention is to provide a device of the character described from which the moisture separated from the steam and vapor may be manually or automatically discharged.

A still further object of the invention is to provide a construction whereby the inlet pipe of the economizer may be coupled to the usual overflow pipe of the radiator in such manner as to provide a yielding joint between them to compensate for all vibrations or variations in the movements of the parts.

A still further object of the invention is to provide a device of the character described which is simple of construction, capable of being sold and installed at a low cost, adapted to be readily and conveniently mounted upon the motor, and designed to form an adjunct which will add to instead of detracting from the appearance of the engine.

The invention consists of the features of construction, combination and arrangement of parts, hereinafter fully described and claimed, reference being had to the accompanying drawing, in which:

Figure 1 is a sectional side elevation of an automobile motor showing the application of our invention thereto.

Figure 2 is a central vertical section through the humidifying device.

Figure 3 is a horizontal transverse section on the line 3-3 of Figure 2.

Figure 4 is a perspective view of the supporting bracket.

Referring now more particularly to the drawing, 1 designates an automobile motor of the water-cooled type, to which the invention is shown in the present instance applied, and 2 designates the cooling radiator having the filling inlet 3 provided with a removable closure cap 4. 5 designates the carbureter and 6 and 6^a the intake and exhaust manifolds, respectively, having the usual branches 7 and 7^a, respectively, leading to the inlet and exhaust ports of the cylinders. In the type of motor disclosed, the branches 7 and 7^a are held fixed against the motor casing by yoke clamps 8 engaging stud bolts 9 and secured in position by nuts 10 on said stud bolts.

In accordance with our invention we provide a fuel economizer and carbon reducer in the form of a humidifier, the same comprising a vertically disposed cylinder 11 closed at its upper and lower ends by threaded caps or heads 12 and 13. The upper cap or head 12 forms a union element having inlet and discharge nipples 14 and 15 for the connection therewith by means of coupling nuts 16 and 17 of the proximate ends of pipes 18 and 19. The pipe 18 forms an overflow pipe leading from the radiator 2 at a point above the normal water line therein, while the pipe 20 provides a vapor feed pipe leading from the humidifier to the carbureter 5. In the operation of the engine, a suction pull is induced in the cylinder 11 and pipes 18 and 19, whereby steam and vapor from the top of the radiator 2 is drawn into the chamber 11, accompanied at times by water rising in the radiator above the normal level when the water in the radiator is unduly heated. In the cylinder 11 the steam and vapor are separated from the free water and water of condensation and flow through the pipe 19 to the carbureter 5 where it commingles with the fuel charge for passage to the engine cylinders, the water being retained in cylinder 11 and flowing by gravity to the bottom thereof.

The cylinder 11 is supported at a convenient point adjacent to the front of the engine and at one side thereof, so that the pipes 18 and 19 may be extended thereto and therefrom without objectionable complica-

tions or kinks or bends in said pipes liable to establish a material resistance to the flow of the fluids. In order to enable the pipe 18 to be coupled to the cap 12, so as 5 to permit said pipe to be disposed for a substantially straight direct flow of the fluid thereto, the nipple 14 is disposed at an oblique angle to the vertical axis of the cylinder 11 and cap 12, while in order to enable 10 the pipe 19 to be disposed, so that said pipe may be extended to the carbureter 5 on as short a line as possible without interfering with the parts of the motor to which access must be afforded, the nipple 15 extends horizontally from one side of the 15 cap 12.

The cylinder 11 forms a separating and collection chamber in which the steam and vapor are separated from the free water and 20 water of condensation and the latter collected and discharged, allowing vapor only to flow through the pipe 19 to the carbureter. In order to secure this separating action in an efficient manner, the cap 12 is provided 25 with a central diaphragm or deflector 20. This deflector 20 is integral with the cap and separates the nipples 14 and 15 from each other, so as to form an indirect path there-between, causing the water and vapor entering 30 through the pipe 18 to pass down into the cylinder 11, the water flowing by gravity into said cylinder while the lighter vapor is drawn by the suction of the engine through the pipe 19 into the carbureter, by which means the passage of any 35 water to the carbureter is avoided in a simple and effective manner. The oblique angular disposition of the nipple 14 provides for the striking of the entering water and 40 vapor at a tangent against the adjacent side of the deflector 20, thus effecting a physical separating action, in addition to that afforded by gravity, all moisture resulting from condensation or about to be condensed 45 being directed by the deflector 20 into the cylinder 11 and prevented from being sucked with the vapor into the pipe 19.

The bottom head 13 of the cylinder 11 is provided with a suitable drain cock 21 50 whereby the water contents of the cylinder 11 may be manually drained therefrom whenever desired. We however also provide an automatic drain device in the form of a siphon for periodically draining the 55 water contents from the cylinder when such contents rise above a certain level. This siphon is of simple type and comprises a central elbow member 22, extending through one side of the cylinder 11, the inner branch 60 being threaded to receive a depending pipe 23 forming a short intake leg of the siphon, while the outer branch of the elbow is fitted to receive a discharge pipe 24 adapted to be connected therewith by a coupling nut 25, 65 said pipe 24 forming the outer longer dis-

charge leg of the siphon. The horizontal arm of the elbow 22 is of the same diameter as the opening in the cylinder through which it passes, thus allowing said elbow to be inserted through the opening and fixedly 70 secured therein in any suitable manner after passage of the elbow into the cylinder via one end thereof. When the elbow is thus fitted in position, the pipes 23 and 24 may be readily and conveniently connected therewith, making this part of the device easy of assemblage. When the water in the lower portion of the cylinder 11 rises up to a predetermined level in the cylinder, it will fill the siphon and overflow in an obvious manner, whereby an automatic discharge of the water at predetermined periods will be effected. The pipe 24 may lead to any suitable point for the discharge of the expelled water upon the ground or 85 for return to the radiator for reuse, as may be desired in service.

In order to adapt the cylinder 11 to be secured in position upon the motor, so that the parts may be disposed in the manner described, a fastening bracket 26 is provided. This bracket comprises a length of strap metal doubled upon itself so as to provide a pair of limbs 27 and 28 joined at one end by a clamping loop 29. The loop 29 is adapted to surround the cylinder 11 between the head 12 and pipe 24, and the material of which the bracket is made may have a suitable degree of resiliency so that in bringing the arms 27 and 28 more or less together the 100 loop 29 will be contracted to tightly grip the cylinder 11. Adjacent to the loop 29 the arms 27 and 28 are preferably provided with registering openings 30 for the reception of a fastening bolt 31 provided with a 105 securing nut 32, whereby the loop 29 may be held in contracted condition and the arms 27 and 28 prevented from springing apart at the point of juncture of the loop therewith. The arms 27 and 28 are of a length 110 for proper adjustable fastening connection with the first two of the four stud bolts 9 and to take the place of the two forward yoke clamps 8 customarily employed for clamping the forward branches of the intake and exhaust manifolds to the motor. For this purpose, the arms 27 and 28 are provided with sets of registering slots 33 for the passage of the stud bolts 9, and for sliding adjustable engagement with said stud 115 bolts so that the bracket may be properly adjusted in position for the dual supporting and clamping action and to dispose the humidifier 11 in proper position, the nuts 11 applied to said stud bolts being tightly 120 turned up to hold the arms 27 and 28 from spreading and the bracket from displacement, as will be readily understood. An additional advantage resulting from this construction of the bracket is that the slight 125 130

tendency of the arms 27 and 28 to spring apart causes the outer arm 28 to frictionally bind against the nuts 10, holding said nuts securely against any possibility of working loose.

In the operation of the device, it will be apparent that the water and vapor flowing through the pipe 18 to the cylinder 11 will be separated in said cylinder, the water being deposited therein while the vapor is drawn off through the pipe 19 and sucked into the carburetor, where it commingles with the fuel charge flowing to the working cylinders. The fuel charge is thus impregnated with a moist vapor which expands therewith into gas in the cylinder, thus humidifying the charge so as to secure its more perfect combustion, thereby increasing its power and reducing the amount of unconsumed particles resulting in carbon deposits. By means of our invention this operation is efficiently carried out during the working of the engine, without the use of complex parts which are difficult or expensive to install.

The device in fact may be manufactured and sold at a comparatively low cost and is of such type that it may be made to serve as an ornamental adjunct to the engine structure.

The pipe 18, as shown, comprises two sections 18^a and 18^b, coupled by an intermediate section 18^c. The section 18^a is preferably in practice the usual overflow pipe which is cut off at a point immediately below the bottom of the top water chamber of the radiator and then joined by a hose connection 18^c and to a short pipe section 18^b which connects with the inlet of the economizer. By this means the economizer may be readily coupled to the usual overflow pipe in such manner that the intermediate or hose pipe section 18^c will form an elastic joint between the pipe members 18^a and 18^b, provid-

ing a positive flow connection and at the same time forming a flexible coupling which will compensate for all vibrations or variations in movements between the radiator and economizer in the travel of the vehicle.

Having thus fully described our invention, we claim:

1. A humidifier of the type described adaptable for insertion between the radiator and intake manifold of an internal combustion engine comprising, a vertically disposed cylinder, caps closing the top and bottom of the cylinder, the top cap being provided with an intake nipple disposed at an oblique angle upon the top portion thereof and connected to the radiator of the engine, and a discharge nipple extending horizontally from one side thereof, and connected to the intake manifold of the engine and also being provided with a vertically depending baffle between said nipples, the intake nipple being arranged to discharge fluids against one side of said baffle, and means for discharging collected water from said cylinder.

2. A humidifier of the class described for insertion between the radiator and the intake manifold of an internal combustion engine, comprising a cylinder closed at both ends, a baffle plate in one of said ends dividing the same into separate chambers each communicating with said cylinder, a liquid nozzle extending into one of said chambers at an angle so as to direct its stream against said baffle plate, an outlet for the other chamber, and means for draining liquid from said cylinder.

In testimony whereof we affix our signatures in presence of a witness.
